CLAIM

The ornamental design for an interior face of an accident identity kit, as shown and described.

DESCRIPTION

FIG. 1 is a perspective view of the interior face of an accident identity kit, showing my new design; and,

FIG. 2 is a perspective view of an alternate embodiment thereof.

The portions of the drawings shown in broken lines are for illustration purposes only and form no part of the claimed design.

1 Claim, 2 Drawing Sheets
